UNITED STATES PATENT OFFICE.

HUGH G. FERGUSON, OF ST. LOUIS, MISSOURI, ASSIGNOR TO UNITED STATES INCANDESCENT LAMP COMPANY, OF ST. LOUIS, MISSOURI, A CORPORATION OF MISSOURI.

SEALING-IN MACHINE.

No. 833,131.

Specification of Letters Patent.

Patented Oct. 9, 1906.

Application filed October 11, 1905. Serial No. 282,256.

To all whom it may concern:

Be it known that I, HUGH G. FERGUSON, a citizen of the United States, residing at the city of St. Louis, in the State of Missouri, have invented a certain new and useful Sealing-In Machine, of which the following is such a full, clear, and exact description as will enable any one skilled in the art to which it appertains to make and use the same, reference being had to the accompanying drawings, forming part of this specification.

My invention relates more particularly to a machine for sealing the filament support or stem of an incandescent electric lamp into the neck of the bulb, and has for its object to provide a machine of this character which will be simple in construction and effective in operation to heat the neck of the lamp uniformly around its entire circumference to seal the stem into the neck.

In the drawings, in which like characters of reference refer to similar parts in the different views, Figure 1 is a side elevation of the apparatus; and Fig. 2 is a top plan view, partly in section, thereof.

10 is the table or platform upon which the various parts are supported, and 11 is a cylindrical standard carried by the table. This standard is provided with upper and lower flanges 12 and with a collar 13, sleeved thereon. This collar carries four laterally-extending arms 14. Each of these arms is provided with a cross-piece 15 and two uprights 16. A lamp-rack 17 is slidably mounted on each set of uprights 16 and made adjustable by a set-screw 18. This lamp-rack is of well-known construction, and it need not be further described here.

20 represents rods passing through perforations in the ends of the arms 14 and cross-pieces 15, in which they are held by friction and adapted to receive on their upper ends the filament supports or stems 21 of the lamps. The filament support or stem is thus held in the proper position for sealing in the necks of the lamps 22.

A forked frame 23 is attached to a collar 24, sleeved upon the standard 11, to support the collar 13. This frame carries at its lower end a link 25, attached to one end of a bent lever 26, pivoted at 27 to the table 10 and provided at its outer end with a weight 28. 29 is a rod for operating this device, as hereinin-

after described. Each of the arms 14 is provided with an extension 30, which is adapted to engage with a stop 31, pivoted at 32 to an upright 33, carried on the table 10. This stop is yieldingly supported by a spring 35 and is provided with a lateral extension 36 whereby it may be operated.

40 is a stud carried by the lower side of the table 10 and having pivotally mounted upon it a swinging member 41. This member 41 carries at its ends two uprights 42, one of which passes upward through the cylindrical support 11. Slots 44 are provided in the table 10 to permit of the movement of these uprights and the member 41, which carries them. Each of the uprights 42 is provided with air-nozzles 45, controlled by valves 46, and with a lateral extension 47, carrying gas-nozzles 48, controlled by valves 49. 50 indicates flexible conduits for conveying the compressed air and gas to these nozzles.

52 is a bracket carried at the lower side of the table 10 and provided with a shaft 53, upon which is mounted an eccentric 54, connected by an arm 55 with the member 41. The shaft 53 also carries a pulley 56, supplied with power from any suitable source by means of a belt 57.

In the operation of my invention the lamp-bulb is first placed in the lamp rack or holder 17 and the filament support or stem 21 inserted therein by means of the sliding rods 20 in proper position to be sealed to the neck of the lamp. During this time the collar 13 is held in its upper position, as shown in Fig. 1, by means of the weight 28. By means of the stop 31 one of the arms 14 is then brought into proper position between the nozzles or burners 45 and 48. In this position the lower end or neck of the lamp is somewhat above the line of the flame, but may be brought into exact alinement with the flame from the burners by moving the collar 13 downward on the support 11 by means of the rod 29. The eccentric 54 oscillates the pivoted member 41 backward and forward to distribute the heat evenly around the neck of the lamp, thus effectually sealing in the stem. While one seal is being completed another bulb and stem are prepared on one of the other arms 14 of the machine and are ready for the operation of sealing by the time the

first operation is completed. It will be seen that in my invention the neck of the lamp is subjected to an evenly-distributed heat by means of the oscillating burner, while the rods 5 16, supporting the lamp-frame, are not subjected to the flame, the oscillation of the burners being insufficient in extent to include them.

Having fully described my invention, what 10 I claim as new, and desire to secure by Letters Patent of the United States, is—

1. The combination with a lamp-holder, of heat-applying means mounted to oscillate about said holder.

15 2. The combination with a lamp-holder, of a burner mounted to oscillate about said holder.

3. The combination with a lamp-holder, of a plurality of burners mounted to oscillate 20 about said holder, and means for actuating said burners.

4. The combination with a lamp-holder, of an oscillating member adjacent thereto, burners carried by said member at opposite 25 sides of said holder, and means for actuating said member.

5. The combination with a movably-mounted lamp - holder, of heat - applying means mounted to oscillate about said 30 holder.

6. The combination with a movably-mounted lamp - holder, of a plurality of burners mounted to oscillate about said holder, and means for actuating said burners.

35 7. The combination with a movably-mounted support, of a plurality of lamp-holders carried thereby, and a burner mounted to oscillate about said holders.

8. The combination with a rotatably-mounted support, of a plurality of lamp-

holders carried thereby, an oscillating member, burners carried by said member at opposite sides of said lamp-supports, and means for actuating said member.

9. In a sealing-in machine, the combination with a hollow standard, of a lamp-holder movably carried thereby, and an oscillating burner-holder extending through said standard. 45

10. In a sealing-in machine, the combination with a hollow standard, of a plurality of lamp - holders rotatably mounted thereon, and an oscillating burner-holder extending through said standard. 50

11. In a sealing-in machine, the combination with a hollow standard, of an oscillating member, a plurality of burner-holders carried by said member, one of said burner-holders extending through said standard, and a plurality of lamp-holders carried by said standard and adapted to be brought successively 55 into the center of oscillation of said member.

12. In a sealing-in machine, the combination with a hollow standard, of an oscillating member, a plurality of burner-holders carried by said member, one of said burner-holders extending through said standard, a plurality of lamp-holders rotatably mounted on said standard and adapted to be brought successively 60 into the center of oscillation of said member, and means for raising and lowering said lamp-holders. 65

In testimony whereof I have hereunto set my hand and affixed my seal in the presence of the two subscribing witnesses.

HUGH G. FERGUSON. [L. S.]
